UNITED STATES PATENT OFFICE

127,722

DESIGN FOR A BUCKLE OR SIMILAR ARTICLE

Fred Gray, New York, N. Y.

Application April 8, 1941, Serial No. 100,225

Term of patent 3½ years

To all whom it may concern:

Be it known that I, Fred Gray, a citizen of the United States, residing at New York, in the county of New York and State of New York, have invented a new, original, and ornamental Design for a Buckle or Similar Article, of which the following is a specification, reference being had to the accompanying drawing, forming part thereof.

Fig. 1 is a plan view of a buckle showing my new design.

Fig. 2 is an end elevational view of the same.

I claim:

The ornamental design for a buckle or similar article, as shown.

FRED GRAY.
